UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 11,861, dated July 13, 1880.

Application filed February 12, 1880. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets, oil-cloths, and similar fabrics.

10 It consists in a novel grouping and configuration of figures, hereinafter more fully described and claimed.

The accompanying photograph illustrates a face view of a carpet having my new design.

15 On the background A of the carpet is a group, B, composed of leafy twigs *a*, interspersed with small flowers; a group, C, composed of leaves *b* and flowers *d*; a group, D, composed of leaves *e* and a flower, *f*; a group, E, composed of leafy twigs *g* and a flower; a group, H, composed of leaves *l* and flowers *m*; a group, I, composed of leaves *n* and flowers *o*; a group, K, composed of leafy twigs *p* and flowers *r*; a group, L, composed of leafy twigs *s* and flowers *t*. Between groups H, I, and K, the background A is thickly strewn with small leaves and flowers, which connect the said groups.

I claim—

30 1. The design for a carpet, which consists of

the group C, composed of leaves *b* and flowers *d*, substantially as shown.

2. The design for a carpet, which consists of the group D, composed of leaves *e* and flower *f*, substantially as shown.

3. The design for a carpet, which consists of the group E, composed of leafy twigs *g* and flowers, substantially as shown.

4. The design for a carpet, which consists of the group I, composed of leaves *n* and flowers *o*, substantially as shown.

5. The design for a carpet, which consists of the group K, composed of leafy twigs *p* and flowers *r*, substantially as shown.

6. The design for a carpet, which consists of the group L, composed of leafy twigs *s* and flowers *t*, substantially as shown.

7. The design for a carpet, which consists of groups H, I, and K and the small flowers and leaves on the background A, which connect the said groups, substantially as shown.

8. The design for a carpet, which consists of the background A, groups B C D E H I K L, and intermediate leaves and flowers, substantially as shown.

HENRY HORAN.
